MILLING MACHINE

Hans Ernst, Mario E. Martellotti, and Walter D. Archea, Cincinnati, Ohio, assignors to The Cincinnati Milling Machine Co., Cincinnati, Ohio, a corporation of Ohio

Application September 10, 1935, Serial No. 39,950

13 Claims. (Cl. 90—21.5)

This invention relates to milling machines and more particularly to an improved transmission and control mechanism therefor.

One of the objects of this invention is to provide an hydraulically operated milling machine which will perform climb cutting operations in a more efficient and practical manner than heretofore.

Another object of this invention is to provide an hydraulic control mechanism of the servo-type in which the servo-valve may be remotely located with respect to the moving part, whereby the entire hydraulic control mechanism may be built as a unit for insertion in the machine.

15 A further object of this invention is to provide a milling machine with a servo-control mechanism while retaining the other desirable features of automatic rate and direction control, selective automatic stop, and variable feed rate selection.

20 Other objects and advantages of the present invention should be readily apparent by reference to the following specification, considered in conjunction with the accompanying drawings forming a part thereof and it is to be understood that any modifications may be made in the exact structural details there shown and described, within the scope of the appended claims, without departing from or exceeding the spirit 25 of the invention.

30 Referring to the drawings in which like reference numerals indicate like or similar parts:

Figure 1 is a front elevation of a machine tool embodying the principles of this invention.

35 Figure 2 is a section through the hydraulic control unit as viewed on the line 2—2 of Figure 1.

Figure 3 is a section on the line 3—3 of Figure 2.

40 Figure 4 is a section on the line 4—4 of Figure 3 showing part of the mechanism for actuating the servo-valve.

Figure 5 is an elevational view as viewed on the line 5—5 of Figure 4 showing the operating connections to the servo-valve.

45 Figure 6 is a detail section on the line 6—6 of Figure 4.

Figure 7 is a detailed section on the line 7—7 of Figure 4.

50 Figure 8 is a detail section through one of the relief valves.

Figure 9 is a detail view of the feed rate throttle and operating connections therefor.

55 Figure 10 is a detail section on the line 10—10 of Figure 3 showing the brake mechanism.

Figure 11 is a sectional view through the rate valve.

Figure 12 is a view showing the operating connections to the stop valve and the pilot valve.

Figure 13 is a detailed section on the line 13—13 of Figure 12.

Figure 14 is a diagrammatic view of the hydraulic control circuit.

Figure 15 is a section through the pilot valve as viewed on the line 15—15 of Figure 12.

Figure 16 is a rolled-out view of the pilot valve plunger.

Figure 17 is a modified form of connection between the table and servo-valve.

Figure 18 is a detail section on the line 18—18 of Figure 17.

A machine embodying the principles of this invention is illustrated in Figure 1 and comprises a bed 10 upon which is formed a guideway for receiving a horizontally movable work table 11. This table is adapted for moving a work piece 12 in a direction transversely to the axis of the cutter spindle 13 upon which a cutter 14 is supported for rotation.

This cutter spindle is journaled in a carrier 15 which is vertically adjustable on guideways 16 through suitable conventional mechanism formed on the column portion 16. This makes it possible for the cutter to be adjusted relative to the work table 11 to determine the depth of cut. A transmission mechanism not shown may be provided for rotating the cutter spindle in either direction and this mechanism may be the same as that shown in co-pending United States application, Serial Number 220,721, filed September 15, 1927, and therefore, further description thereof is not believed to be necessary.

In milling machine practice there are two recognized ways in which a cutting operation may be performed and these are differentiated by the direction in which the cutter rotates as respects a common feeding direction of the table. In other words, the cutter may be rotated counterclockwise, as viewed in Figure 1, and the table moved to the left, in which case it will be apparent that each cutter tooth exerts a force in a direction opposed to the direction of movement of the table, or in other words, the cutter opposes the force that feeds the table. On the other hand, the cutter may be rotated in a clockwise direction with the table still being moved toward the left, which results in the cutter tooth tending to advance the table in the same direction in which it is feeding.

In the latter case, the feeding mechanism has

to exert a force in such a direction and of sufficient amount to overcome any tendency for the cutter to usurp the function of the feeding mechanism and yet maintain a uniform feed rate if the work is to be properly finished. Although hook-in cuts, as the latter are known in the art, have been accomplished in the past, the results have not been very satisfactory. This invention deals with a mechanism which makes it possible to take the hook-in cut in a very steady manner and with no perceptible difference in results than if the cut were taken in another manner.

The transmission and control mechanism forming the basis of this invention is hydraulic in nature but differs from known hydraulic circuits for this purpose in that a servo-motor mechanism is utilized and even this mechanism is so contrived that the servo-valve may be remotely located with respect to the moving part. This is accomplished by using a servo-valve of the repositioning type as distinguished from the follow-up type whereby the servo-valve housing and its plunger remain in substantially a fixed position at all times.

The entire hydraulic mechanism is mounted in a single bracket which may be removed and inserted as a unit in the bed of the machine and constitutes in a sense a centralized power unit. The table is actually moved by a piston 17 contained in a cylinder 18 and connected by a piston rod 19 to one end of the table. The cylinder may be mounted on the top of the bed, as shown in Figures 1 and 3, and intermediate the table guideways formed thereon while the servo-valve indicated as a unit by the reference numeral 20 may be located in a bracket 21 which is detachably mounted on one end of the bed whereby the servo-valve is remotely located with respect to the table 11 and cylinder 18. The connections to this valve from the cylinder are shown in Figure 14, and comprise a channel 22 which extends from port 23 of the servo-valve to the right hand end of the table cylinder and a channel 24 which extends from port 25 to the left hand end of the table cylinder. This valve has a pressure port 26 which is connected by channel 27 to the output 28 of a constant pressure variable delivery pump 29, which is commercially known as an accumulator pump.

The servo-valve also has ports 30 and 31 which are connected by a common return line 32 to the intake side 33 of the accumulator pump. The output 28 of the pump is connected by channel 34 to a cylinder 35 in which is contained a piston connected to pump pendulum, a spring being utilized to exert an opposing force to the hydraulic pressure whereby when the pressure rises too high the pendulum will be moved in a direction to reduce the volumetric flow from the pump, and when the pressure drops the pendulum will be moved in a direction to increase the flow.

The servo-valve has a central spool 36, which is slightly narrower than the width of the port 26, to allow a continuous flow from the pressure port past both sides of the spool when the same is in a central position, or the spool may be slightly greater in width than the width of the annular groove but with the corners beveled a sufficient amount to still permit a continuous flow from the annular groove 26 when the spool 36 is central with respect to the port. The space allowed for the flow, however, is very small and constitutes, in effect, a pair of hydraulic resist-

ances connected in parallel to the port 26 whereby a pressure drop will occur between this port and the spaces formed around the valve plunger 37 by the cannelures 38 and 39. In addition, these cannelures are of sufficient axial length that there is some flow from each cannelure through each port 30 and 31 when the spool 36 is centrally located with respect to the pressure port. The result of this is that there is formed an hydraulic resistance to the flow of fluid from the cannelures to the channel 32, causing another drop in pressure, whereby the pressure in channel 32 is lower than the pressure in either cannelure and the pressure in either cannelure is lower than the pressure in the supply channel 27. Since the ports 23 and 25 are in continuous connection with these cannelures, the pressures existing therein will be communicated to opposite ends of the cylinder whereby a substantial holding pressure exists therein at all times, regardless of whether the table is stationary or moving. This distinguishes from other servo-valve mechanisms in which the spool 36 is of equal width with respect to the pressure port so that when the servo-valve is in a central position no flow occurs to the cylinders; and also in the fact that even when the valve is moved from its central position there is still some division of flow whereby the pressure in either end of the cylinder never drops to atmospheric pressure.

In order to cause movement of the table it is necessary to move the servo-valve piston from its central position.

One form of servo-valve operating mechanism is shown in Figures 3, 4 and 5. In Figure 5 it will be noted that the servo-valve plunger 37 is connected to a rod 40 having a head 41 on the end thereof and a spring 42 is interposed between this head and a bracket 43 fixed to the valve housing whereby the spring tends to cause movement of the plunger 37 toward the right. The rod 40, however, abuts the end of a slideable rod 44 which, in turn, is interposed between the end of the head 41 and a lever arm 45. The opposite side of the lever 45 is engaged by a button 46 carried by the lever arm 47, this lever arm being bolted to a disc 48 fixed with a shaft 49, as more particularly shown in Figure 4.

The shaft 49, as shown in Figure 6, has a pinion 50 secured thereto which intermeshes with a pinion 51, which, in turn, engages an internal gear 52. As shown in Figure 4, this internal gear is integral with a worm gear 53 meshing with a worm 54.

Referring to Figure 3, the worm 54 is journaled at opposite ends in anti-friction bearings 55 and 56 and at one end has an operative connection to an hydraulic motor 57 and at the other end a selective clutch connection to a hand wheel 58. This connection comprises a clutch member 59 which is fixed with the shaft 60 which supports the worm 54, and a shiftable clutch member 61 which is slidably mounted on the end of a rotatable shaft 62. A spring 63 is mounted interiorly of the shaft 62 and engages a cross pin 64 fixed with the member 61 by which the same is connected for rotation with the shaft 62 and acts in a direction to maintain engagement of the clutch whereby the hand wheel 58 is normally connected to the shaft 60. The shaft 62, however, has a shoulder 65 formed thereon which is mounted in a cylinder 66 whereby when fluid pressure is admitted to this cylinder, the shaft 62 will be moved in a direc-

tion to disengage the clutch teeth. The hydraulic connections are such that pressure will be admitted to this cylinder at all times when the machine is being power operated.

5 If it is assumed that the member 61 is in engagement with the member 59 the hand wheel 58 may be rotated, thereby causing rotation of the worm wheel 53, and through the internal gear 52 and pinion 51, will cause rotation of the pinion 50 and thereby movement of the arm 47 shown in Figure 5 in a clockwise direction, which will shift the servo-valve plunger 37 to the left and cause admission of fluid through one of the channels 22, 24 to the cylinder 18, and thereby 15 movement of the table.

Movement of the table is transmitted to the servo-valve to reposition the same by means of a steel tape 67 which is connected at one end to the table by means of bolts 68, and at the other 20 end to a reel 69. The tape passes over the roller 78 located on top of the bracket 21. The reel 69 has a removable section 71 by which the same 25 may be securely anchored to the reel. The reel 69 is secured by a set screw 72 to shaft 73, Figure 4, this shaft having a spur gear 74 fixed therewith and intermeshing with gear 75. The gear 75 is supported for free rotation about the sleeve 76 in which the shaft 49 is journaled. The gear 75 has the pinion 51 secured thereto whereby upon rotation of the reel, the planetary gear 51 will be moved, and since the internal gear 52 is held stationary by the intermeshing worm and worm gear 53, 54 the pinion 50 will be rotated in a direction to cause movement of the arm 47 in 30 an opposite direction to that in which it was moved by the hand wheel 58 whereby the servo-valve will be returned to a central position and movement of the table will be stopped.

Although it would seem from the foregoing 40 description that there is considerable time elapse between rotation of the hand wheel 58 and the return movement from the table, there is actually no perceptible time lapse, the repositioning movement occurring to all intents and purposes 45 almost simultaneously with the initiating movement.

The mechanism for causing power feeding movement of the table at a uniform rate consists of the hydraulic motor 57 which may be 50 rotated at variable feed rates or at a fast or quick traverse rate and since the energy required to rotate the worm and worm wheel and move the servo-valve is very small, this motor may of course be of a very light type.

55 As shown in Figure 14, of the drawings this motor 57 has a pair of ports 77 and 78 which are connected by channels 79 and 80 to ports 81 and 82 of a stop valve 83 having a plunger 84. This valve plunger has a cannelure 85 and a second 60 cannelure 86 which, when the plunger is in a running position, connects ports 81 and 82 to ports 87 and 88 respectively. The port 87 is connected by channel 89 to ports 90 and 91 of a direction control valve 92 having a reciprocable 65 plunger 93. The port 88 is connected by channel 94 to port 95 of the direction or reversing valve 92. When the plunger 93 is in one position, a cannelure 96 therein connects port 95 to the exhaust port 97, and a cannelure 98 connects 70 port 91 with a pressure supply port 99. If the plunger is shifted toward the right to its other extreme position, the pressure port 99 is connected to port 95 and port 90 is connected by cannelure 100 to port 97 which will thereby cause 75 rotation of the motor 57 in an opposite direction.

Pressure is supplied to the port 99 from the following source. A constant delivery pump 101, having an intake 102 through which fluid is withdrawn from a reservoir 103, delivers fluid into a channel 104 which has a connection to 5 port 105 of the rate control valve 106 in which is reciprocably mounted a plunger 107. When this plunger is in the position shown, a cannelure 108 therein connects port 105 to port 109, and thereby, through channel 110, to port 111 10 of the servo-control valve. The servo-valve has an annular groove 112 formed therein which is adapted to connect port 111 with port 113 at all times during normal movement of the valve. The port 113 is connected by channel 114 to the 15 pressure port 99. The object of providing the connection through the servo-valve is merely for safety reasons so that in case the servo-valve gets too far ahead of the movement of the table the supply to the motor 57 will be automatically 20 reduced.

The exhaust port 97 of reversing valve 92 is connected by channel 114 to port 115 of the rate valve, and thereby through cannelure 116, when the valve is in the position shown, to port 117 25 and thereby, through channel 118, to port 119 of the throttle valve 120. This throttle valve has a plunger 121, which may be variably set by rotation of the configurated cam 122 to various positions to control the rate of rotation 30 of the hydraulic motor 57 and thereby the feed rate imparted to the table. A spring 123 maintains the plunger in engagement with the periphery of the cam 122. This valve has an exhaust port 124 which is connected by channel 125 to 35 the reservoir 103.

To insure that the line 110 is properly supplied with fluid, a check valve 126 is interposed for connecting the return channel 32 of pump 29 to channel 110 and the check valve is set 40 to insure additional flow into the channel when the pressure therein drops below a predetermined minimum. The channel 110 also has a connection at 127 to port 128 of a relief valve 129.

The specific construction of this relief valve 45 is shown in Figure 8 and comprises a plunger 130 which is acted upon at one end by a spring 131 which may be set to yield desirable pressures by adjustment of the sleeve 132 in which the spring is contained. This plunger has a cannelure 133 by which port 128 may be interconnected to an exhaust port 134. The plunger also has a diametrical bore 135 which communicates with an axial bore 136 in which is mounted a spring pressed ball 137 which normally acts to 50 close the axial bore and prevent discharge of fluid through port 129. The spring 138 which acts on the ball 137 is a high tension spring and the spring 131 normally acts to position the plunger 130 so that the port 128 is entirely closed. 55 Should a high pressure result at port 128 it will act to open the relief valve ball 137 and cause a flow to the chamber 139 which will act, in turn, on the end of the plunger and shift the same against the resistance of spring 131 60 sufficient to cause the cannelure 133 to interconnect port 129 with port 134. The chamber 139 may be connected by a channel 140 to channel 118. It will be remembered that the channel 118 is the return channel from the motor 57 and 65 that the pressure existing therein will be communicated to the right hand end of valve 129 normally urging the same to an open position. The spring 131 will be so set, however, that this 70 will not occur unless an excessive high pressure 75

occurs in channel 110 due to resistance of the motor, at which time the additional fluid escaping past the high pressure relief ball 137 will cause the pressure in chamber 139 to rise sufficiently to overcome the resistance of spring 131.

A second relief valve 141, which is exactly of the same construction as the relief valve 129, has its port 142 connected to a branch line 143 of channel 104. The chamber 139 of this valve 141 is connected by a channel 144 to reservoir, but this channel has a choke coil 145 arranged therein, which in effect is an hydraulic resistance which will maintain a small predetermined pressure in chamber 139. The channel 144 has a branch 146 which is connected to port 147 of the stop valve 83. The function of this connection is that when the stop valve is shifted to the left from the position shown in Figure 14 to a stop position to interconnect ports 87 and 88, a considerable rise in pressure occurs, due to the sudden stoppage of flow and this rise in pressure is immediately communicated through the connections described to chamber 139 of the relief valve 141. Should this pressure rise beyond a predetermined amount determined by the setting of the valve 141 the plunger 148 of the valve will shift to interconnect port 142 to port 149, and thereby relieve the pressure in channel 104. The discharge from port 149 is delivered into channel 110 which is the motor supply line.

The pump 101 is connected to a check valve 150 to the supply line 27 of the servo-valve. During feed movements of the table the pressure in line 27 is considerably higher than the pressure in line 104 and the check valve 150 will normally remain closed. During quick idling movements of the table at rapid rates, the pressure in line 27 will naturally drop, and the pump 101 is then enabled to augment the delivery of pump 29 and insure a plentiful supply of fluid to maintain the rapid movement.

Since the pump 29 is connected in substantially a closed circuit with the cylinder 18, a bypass valve has been provided whereby the pump 101 may be enabled to fill this closed circuit with fluid from the reservoir 103 when the machine is first started. The valve 151 is utilized for this purpose, and has port 152 connected by branch 153 to the delivery of pump 101, and a second port 154, which is adapted to be connected to port 152 by the cannelure 155, formed in the valve plunger 156. When no pressure exists in the lower end of the valve the spring 157 moves the plunger so that the ports are interconnected and fluid will flow through channel 158 to the intake port of pump 29. When the pressure in the return line of pump 29 rises to a predetermined maximum the fluid leaking through the hydraulic resistance 159 to the lower end of plunger 156 will cause the same to move against the resistance of spring 157 and close port 154. This valve thus acts to automatically supercharge the return line of pump 29 when the machine is first started or at any time that the fluid supply in the circuit falls below a predetermined minimum.

The mechanism for operating the stop valve is more particularly shown in Figure 12 and from that figure it will be noted that a spring 160 is interposed between an abutment 161, and a flange 162 formed on the plunger 84 normally acts in a direction to shift the valve to the left, or in other words, to a stop position. The plunger 84, however, has a lost motion connec-

tion at 163 with a crank arm 164, which has a manual control lever 165 integral therewith. A second crank arm 166, integral with lever 165, has a ball-shaped end 167 interfitting in a slot 168 formed in the end of rod 169. This rod is connected through the bell crank 170 to the latch pawl 171. This pawl interfits in a slot 172 formed in the member 84 to hold the same in the position shown against the compression of spring 160. The bell crank 170 also has a connection at 173 with a stop trip plunger 174. This plunger is surrounded by a spring 175 which is interposed between an abutment 176 and flange 177 formed on the plunger, which normally acts in a direction to move the plunger vertically upward. This movement is limited, however, by the pawl 171 bearing on the rod 84. This insures that the pawl 171 will drop into the slot 172 at any time that the plunger 84 is moved to a position to permit this. The manual or control lever 165, when rotated in a clockwise direction, as viewed in Figure 12, will first move the rod 169 to the left, causing withdrawal of the pawl 171 and the lost motion in connection 163 will permit this to be done. When the pawl 171 has been removed from the slot, the spring 160 will come into action to shift the stop valve to its stop position.

This may also be accomplished automatically by means of a stop dog 178 which may be secured in a T slot 179 formed in the edge of the table 11.

It will be recalled that earlier in the specification reference was made to the fact that the cylinder 66 associated with the clutch 61 that determines the coupling of the hand wheel 58 with the worm 54 was supplied with pressure when the machine was being power operated, and this supply of pressure comes from the high pressure channel 27 through an hydraulic resistance 130. This resistance may be in the form of a choke coil which will cause a considerable drop in pressure to channel 181 which leads to this cylinder. This channel, however, has a branch 182 which is connected to port 183 of stop valve 83. When the stop valve plunger is shifted to the left to a stop position, the port 183 is connected to reservoir through the end of the valve housing due to the fact that the spool 184 has moved a sufficient distance to accomplish this result. From this it will be seen that even though there will be a continuous leakage through the choke coil 130 there will not be sufficient to build up pressure in cylinder 61 due to the open connection at port 183, whereby the operator is enabled to move the rod 65 longitudinally to effect engagement of the clutch. This acts as an interlock and insures that the operator can only utilize the manual control lever 58 when the hydraulic motor 57 is rendered inoperative by the stop valve. Channel 181 also has a branch connection to a brake 181' whereby the brake is held in a released position against resistance of a spring as shown in Figure 10. This brake insures prompt stopping of worm 54.

Since the stop valve merely closes ports 81 and 82, fluid will still remain in channels 79 and 80 and in order to facilitate manual rotation, since the motor 57 is at all times connected to the worm 54, a by-pass valve has been formed in the shaft 62 and consists of a cannelure 185 adapted to interconnect ports 186 and 187 which are connected respectively by channels 188 and 189 to the motor ports 77 and 78 whereby when 75

the motor is rotated due to rotation of the shaft 60 the fluid will freely flow from one side of the motor to the other.

The rate and direction valve plungers are power shifted under the direction of a pilot valve 190, which has a plunger 191 in which is formed three cannelures 192, 193 and 194. This valve has a port 195 which is connected by channel 196 to a high pressure channel 27. This valve also has a pair of ports 197 and 198 which are connected by channels 199 and 200 to opposite ends respectively of the direction determining or reversing valve 92. When the valve plunger 191 is in the position shown, the port 198 is connected to the pressure port 195 and fluid is delivered through channel 200 to the right hand end of the direction valve which shifts the same to the position shown and the other end of the direction valve is connected through channel 199 and port 197 to annular groove 192. This groove has a radial hole 201 which intersects an axial bore 202 which extends the full length of the valve plunger, and is at all times connected with reservoir through a second axial hole 203 which communicates with the annular groove 194. This groove, at all times, communicates with port 204 which is connected by channel 205 to the return line 125. When the valve is shifted to the left the pressure port 195 is connected to port 197 which causes shifting of the valve plunger 93 to the right and channel 200 is connected through port 198 to the exhaust annular groove 194.

Thus, by merely shifting the pilot valve axially the direction of movement of the table may be reversed.

The pump 57 is rotated at a fast or quick traverse rate when the rate control valve plunger 107 is shifted to the right from the position shown in Figure 14. At this time, the pressure port 105 from pump 101 is disconnected; the port 109 isolated; and the port 115 interconnected to the return line 125.

Fluid is now supplied to motor 57 from pump 45 101 through port 142 of valve 141, the plunger of which opens sufficiently to permit flow through port 149 to channel 110. The flow in this channel is augmented through the check valve 126. The return flow from the motor 50 passes through channel 114 to the return line 125. Thus, during rapid traverse movement of the table the throttle valve does not function but whatever pressure exists at port 117 is communicated to the right hand end of valve 129 to cause opening of port 128 to reservoir, should there be an excess of fluid in channel 110.

The feed-rapid traverse or rate selector valve 106 has channels 206 and 207 leading from opposite ends thereof to ports 208 and 209 of the pilot valve. This valve also has a pressure port 210 which is connected by channel 211 to ports 212 and 213 of the reversing valve 92. The object of this is that when both the direction and rate valve have to be shifted at the same time 65 that the direction valve will be shifted first, thereby cutting off the supply to port 210 until the direction valve has completed its movement.

The pilot valve has two longitudinal slots 214 and 215 formed therein, and another pair similarly located but in 180° phase relation thereto. The plunger also has a second pair of slots 216 and 217 formed in 180° phase relation with one another, but in 90° phase relation with respect to grooves 214 and 215 and also in overlapping relation thereto. The plunger also has four exhaust

grooves 218, 219, 220 and 221. When the plunger is in the position shown, the port 210 is connected by groove 217 to port 209 and pressure is delivered to the right hand end of the rate valve and the left end is connected, through channel 5 206, port 208 and exhaust groove 219, to reservoir. This valve is rotatable through 22½° from the position to change the rate without changing the direction, from which it will be seen that a 22½° rotation of plunger 91 will position groove 10 214 opposite holes 208' and 210' formed in port grooves 208 and 210, thereby connecting pressure to the left end of the rate valve 106 and thereby shifting the same to the right and connecting channel 207 through port 209 to longitudinal groove 215. This groove is at this time in communication with a hole 222 in the bushing which, as shown in Figure 15, communicates with an annular groove 223, this groove being connected at this time by a second hole 224 in the 20 bushing to the exhaust bore 202.

If the plunger 191 is shifted to the left from this position the groove 215 will now interconnect the pressure port 210 to port 209 and groove 217 will interconnect port 208 to exhaust in a manner similar to that shown in Figure 15. In other words, each time the valve plunger 191 is shifted longitudinally from one position to the other or rotated while in either one of these extreme positions, the rate of movement of the table is 30 changed. All of these various connections are shown in the expanded view of the pilot valve shown in Figure 16 of the drawings.

The valve plunger 191 is connected through a universal joint 225, as shown in Figure 13, to 35 the trip plunger 226 which has a wing 227 on one side thereof adapted to be engaged by dogs 228 and 229 to rotate the same to shift the plunger 191 longitudinally. The plunger 226 is also supported for vertical movement and has 40 a pair of lugs 230 and 231 adapted to be engaged by dogs 232 and 233 for shifting the same vertically and thereby rotating the valve. In other words, the rate may be changed during continuous movement in either direction without changing the direction. But when the plunger 226 is rotated to change the direction it also changes the rate. This makes it possible to change from feed in one direction to a quick traverse movement in the other direction by a single movement 50 of the valve. The plunger 191 may be provided with a manually operable handle 234 whereby the position of the valve may be determined by the operator.

In Figure 17 of the drawings is shown a modified form of connection between the table 11 and the servo-control valve and comprises a rack 235 which is attached to the table and operatively engages a spur gear 236 mounted on shaft 237 which has integral therewith a bevel gear 238. 60 This bevel gear intermeshes with a bevel gear 239 secured to the upper end of a shaft 240 which extends in an angular relation to the servo-valve housing. The lower end of this shaft has a beveled gear 241 intermeshing with a bevel gear 242 which is integral with the worm 243 which intermeshes with the worm 54 which is the same as the worm shown in Figure 3. In this construction the shaft which supports the worm wheel has a shoulder 244 against which bears 70 a bronze ring 245 having a slot 246 formed therein. A finger 247 interfits in this slot and is part of a lever 248 which is pivoted at 249. The end of the lever 248 abuts the servo-valve plunger 40. The bronze bushing 246 serves to 75

reduce line contact and wear on the end of the finger 247. With the exception of the change in the mechanical construction of this return connection to the servo-valve the operation is 5 exactly the same.

There has thus been provided an improved machine for the purposes disclosed which is simple to construct and operate.

What is claimed is:

- 10 1. Means for effecting relative feeding of the table and cutter of a machine tool including a piston and cylinder, one of which is connected to the table and the other fixed, a servo-valve having a plunger in which is formed chambers 15 which are connected to opposite ends of the cylinder, a source of pressure, fluid resistances for connecting said source of pressure to said chambers, additional fluid resistances connecting said chambers to exhaust whereby a predetermined pressure exists in said chambers and thereby in opposite ends of the cylinder, means to inversely vary the resistances between said pressure port and said chambers to cause a pressure differential in said cylinder and resultant 20 movement of the table to cause the same to move at a predetermined rate unaffected by said cutter, and connections from said table and effective upon said resistances to reversely change the values thereof if the rate of movement fluctuates 25 due to action of the cutter.

2. A feed control mechanism for a milling machine or the like having a bed, a table reciprocably mounted upon the bed and a cutter supported by the bed for rotation in a direction whereby the teeth will move in the same direction as the work during contact therewith, including a cylinder supported by the bed and a contained piston operatively connected to the table, a source of pressure, a pair of variable hydraulic resistances connected to said source of pressure, said resistances terminating in chambers at opposite ends of the cylinder, a second pair of variable hydraulic resistances connecting said chambers to reservoir whereby pressures will be created in said chamber intermediate the supply pressure and atmospheric pressure, means to inversely vary the first pair of resistances to cause a pressure differential in opposite ends of the cylinder to cause movement 45 of the table at a predetermined rate, and means responsive to abnormal movement of the table created by the cutter to readjust said resistance and correct for the action of the cutter.

3. Power operable means for effecting relative movement between the tool and work supports of a milling machine or the like including an hydraulic motor, a source of pressure, a centralized control unit remotely located with respect to said motor, a servo-valve mounted in said unit, means for shifting said valve to cause a flow to said cylinder and thereby operation of one of said supports, and a remote connection from said support to said valve including a steel tape operatively connected to the support, a reel to which the other end of said tape is connected, said reel being located in the unit, and a differential mechanism responsive to movement of the reel for repositioning said servo-valve and reduce the actuating flow to said cylinder.

4. Power operable means for effecting relative movement between the work and tool supports of a machine tool comprising a servo-motor mechanism including a servo-valve, an hydraulic motor for actuating said valve in one

direction, means operatively connecting the valve to one of said supports to cause repositioning of the valve, a control circuit for said motor including a source of pressure, a direction determining valve, a pilot valve for controlling power shifting of the direction valve, and a trip controlled plunger for actuating said pilot valve.

5. The combination with a servo-motor mechanism for actuating a machine tool support, of an hydraulic motor for power operating the servo-valve, a source of fluid pressure, a reversing valve and a stop valve serially connected between said source of pressure and said servo-valve, a pair of channels extending from the stop valve to the motor, said stop valve also having a pressure intake port and a return port connected to said reversing valve, a relief valve in the pressure line, means in the stop valve to interconnect said pair of ports to disconnect flow from the motor, and means connecting the stop valve to said relief valve whereby sudden high pressures created at the intake port of said stop valve upon movement to a stop position will open said relief valve to lower the incoming pressure.

6. Means for actuating a movable support including a piston and cylinder, one of which is connected to the movable support, a servo-valve, a high pressure pump connected in closed circuit to said servo-valve, an hydraulic motor for actuating said servo-valve, a return connection from the movable support for repositioning said servo-valve, a separate source of pressure for actuating said motor including a rate valve, a direction determining valve, and a stop valve in the order named, means to position said rate valve to connect said additional source of pressure to said motor for quick traverse operation thereof, a throttle valve, and means in said rate valve upon movement to a second position to connect the return line from said motor to said throttle valve to cause operation of said motor at a variable feed rate.

7. An hydraulic control system for a milling machine or the like having a work support, and a tool support, including means for effecting relative movement between the supports including a piston and cylinder, each connected to one of the supports, a high pressure accumulator pump, valve means for connecting opposite ends of said pump to opposite ends of the cylinder, said valve means including a first pair of hydraulic resistances connected in parallel to the output of said pump, a second pair of hydraulic resistances connected in parallel to the input of said pump, power operable means for simultaneously increasing one of said first pair of resistances and decreasing the value of the other to increase the pressure in one end of the cylinder and decrease the pressure in the other end, said power operable means also being effective to inversely vary the second pair of resistances to maintain said pressure differential during relative movement of the supports, and means operable by said movement tending to equalize the total pressures in opposite ends of the piston to thereby stop the relative movement between the supports.

8. A transmission for a milling machine having a bed, a cutter spindle rotatably supported by the bed, and a work table mounted on the bed for relative movement transversely to the axis of said spindle, said transmission means including a first hydraulic motor having a piston connected to the table, a servo-valve located in the bed for controlling actuation of said

motor, a second hydraulic motor for actuating said servo-valve, an extensible connection from the table for repositioning said valve, and means to supply fluid pressure to each of said 5 motors.

9. Transmission means for effecting relative movement between the spindle and table of a milling machine or the like in a direction transversely to the axis of said spindle including a 10 cylinder having a piston operatively connected for effecting said relative movement, means to control actuation of said piston including a first pair of serially arranged hydraulic resistances, and a connection between said resistances to one 15 end of the cylinder, a second pair of variable hydraulic resistances, and an intermediate connection to the other end of said cylinder, means to pump fluid through said resistances whereby the pressure in opposite ends of said cylinder will 20 depend upon the ratio of the resistances of one pair to the ratio of the resistances of the other pair, power operable means for continuously changing said ratios in a manner to create a pressure differential on said piston, and means 25 responsive to movement of the table to change said resistances in an opposite manner to reduce the pressure differential on said piston.

10. Means for effecting relative movement or machine tool parts such as a support and table 30 including a piston and cylinder, one of which is connected to the table, a servo-valve for controlling operation of said motor, a second hydraulic motor for actuating said servo-valve, means to supply fluid pressure to each of said 35 motors, a feed back connection from the table to said servo-valve, means to predetermine the rate of operation of said second hydraulic motor and thereby predetermine the feed rate of said table, and means responsive to undesirable 40 changes in the feed rate effected by said cutter to readjust said servo-valve.

11. Transmission means for control of the table of a milling machine having a tool spindle and a toothed cutter supported for rotation 45 thereby and a work table actuatable in a direction parallel to the direction of movement of the teeth of said cutter while cutting, said transmission means including a piston and cylinder, one of which is operatively connected to the table, a 50 constant high pressure pump for delivering fluid to said cylinder, a servo-valve for connecting said pump in a manner to create equal resultant pressures in opposite ends of said cylinder to hold the table against movement, a second hydraulic motor for adjusting said servo-valve to 55 create a sufficient pressure differential to cause feeding movement of the table at a predetermined rate, and means responsive to abnormal changes effected in said rate by the action of said

cutting teeth during cutting to change said pressure differential in a manner to re-establish said predetermined rate.

12. Transmission means for control of the table of a milling machine having a tool spindle 5 and a toothed cutter supported for rotation thereby and a work table actuatable in a direction parallel to the direction of movement of the teeth of said cutter while cutting, said transmission means including a piston and cylinder, 10 one of which is operatively connected to the table, a constant high pressure pump for delivering fluid to said cylinder, a servo-valve for connecting said pump in a manner to create equal resultant pressures in opposite ends of said cylinder 15 to hold the table against movement, a second hydraulic motor for adjusting said servo-valve to create a sufficient pressure differential to cause feeding movement of the table at a predetermined rate, means responsive to abnormal 20 changes effected in said rate by the action of said cutting teeth during cutting to change said pressure differential in a manner to re-establish said predetermined rate, a second pump for supplying fluid to said second motor, 25 connections between the said pump and motor including a reversing valve, and means trip operable by the table for controlling the shifting of said valve.

13. Transmission means for control of the 30 table of a milling machine having a tool spindle and a toothed cutter supported for rotation thereby and a work table actuatable in a direction parallel to the direction of movement of the teeth of said cutter while cutting, said transmission 35 means including a piston and cylinder, one of which is operatively connected to the table, a constant high pressure pump for delivering fluid to said cylinder, a servo-valve for connecting said pump in a manner to create equal resultant 40 pressures in opposite ends of said cylinder to hold the table against movement, a second hydraulic motor for adjusting said servo-valve to create a sufficient pressure differential to cause feeding movement of the table at a predetermined rate, means responsive to abnormal 45 changes effected in said rate by the action of said cutting teeth during cutting to change said pressure differential in a manner to re-establish said predetermined rate, a pump for supplying fluid to said second motor, a feed rapid traverse selector valve and a reversing valve for connecting said last-named pump and motor, and a dog carried by the table for controlling trip actuation of each of said valves. 50
